UNITED STATES PATENT OFFICE

120,008

DESIGN FOR A FASTENER PRONG RING

Otto J. Huelster and Jerome G. Wolff, Waterbury, Conn., assignors to Scovill Manufacturing Company, Waterbury, Conn., a corporation of Connecticut

Application January 27, 1940, Serial No. 89,781

Term of patent 7 years

To all whom it may concern:

Be it known that we, Otto J. Huelster and Jerome G. Wolff, citizens of the United States, residing at Waterbury, county of New Haven, State of Connecticut, have invented a new, original, and ornamental Design for Fastener Prong Rings, of which the following is a specification, reference being had to the accompanying drawing, forming part thereof.

Fig. 1 is a top view of a fastener prong ring embodying our new design, and
Fig. 2 is a front elevation thereof.

We claim:
The ornamental design for a fastener prong ring, substantially as shown.

OTTO J. HUELSTER.
JEROME G. WOLFF.
